[57] CLAIM

The ornamental design for a shoe upper, as shown and described.

DESCRIPTION

FIG. 1 is a left side elevational view of a shoe upper showing our new design;
FIG. 2 is a right side elevational view thereof;
FIG. 3 is a top plan view thereof;
FIG. 4 is a front elevational view thereof;
FIG. 5 is a rear elevational view thereof;
FIG. 6 is a left side elevational view of a shoe upper showing an alternate embodiment of our new design;
FIG. 7 is a right side elevational view thereof;
FIG. 8 is a top plan view thereof;
FIG. 9 is a front elevational view thereof; and,
FIG. 10 is a rear elevational view thereof.
The broken line showing of a shoe sole in FIGS. 1-10 is environmental only and forms no part of the claimed design.

FIG. 1

FIG. 2

FIG. 3

FIG. 4

FIG. 5

FIG. 6

FIG. 7

FIG. 8

FIG. 9

FIG. 10

UNITED STATES PATENT AND TRADEMARK OFFICE
CERTIFICATE OF CORRECTION

PATENT NO. : Des. 352,387
DATED : November 15, 1994
INVENTOR(S) : Poetsch, et. al.

It is certified that error appears in the above-identified patent and that said Letters Patent is hereby corrected as shown below:

Title page, item [19], after Poetsch insert--er al.--therefor.
Title page, item [75], inventors: insert the following name, Peter Backus,
Portland, Oregon.

Signed and Sealed this
Twenty-fourth Day of January, 1995

Attest:

BRUCE LEHMAN
